UNITED STATES PATENT OFFICE.

THOMAS J. CLAYTON, OF PORT ARTHUR, TEXAS.

LUBRICATING DEVICE.

1,154,095.

Specification of Letters Patent. Patented Sept. 21, 1915.

Application filed August 12, 1914. Serial No. 856,358.

To all whom it may concern:

Be it known that I, THOMAS J. CLAYTON, a citizen of the United States, residing at Port Arthur, in the county of Jefferson and State of Texas, have invented certain new and useful Improvements in Lubricating Devices; and I do hereby declare the following to be a full, clear, and exact description of the invention, such as will enable others skilled in the art to which it appertains to make and use the same.

My invention relates to the construction of lubricating devices for automatically and intermittently supplying a lubricant to moving parts of machinery, and is generally applicable for such purposes, but has been especially devised by me for lubricating the flanges of locomotive drivers, and consequently is hereinafter illustrated and described as so applied but without intention of limiting the invention thereto.

As is well understood by those skilled in the art, loss of power as well as loss by wear of parts, incident to the friction of the moving and co-acting machine elements, are matters necessary to be overcome if good results and saving of expense are desired, and nowhere is this more gravely the case than in railway practice where preservation of the tread and wheel flanges of rolling stock is a matter not only of economy but often of safety. It is also well understood that under such conditions the lubricating devices should be simple to insure their durability and effectiveness, and to facilitate repair, and also automatic in their operation to eliminate the probability of their becoming ineffective by reason of hard usage or lack of attention.

To meet these requirements in lubricating devices is the object of my present invention; and to this end my invention, generally stated, consists in the combination in a lubricating device, of a lubricant reservoir, a conduit leading therefrom to the part to be lubricated, an automatically actuated valve for intermittently controlling the flow of the lubricant through the lubricant conduit, and a steam conduit which incloses the lubricant conduit, and delivers thereto at a point between the valve and the part to be lubricated to maintain the fluidity and effect the proper feed and delivery of the lubricant.

There are other features of invention involving particular combinations of ele-

ments, and particular features of elemental construction, all as will hereinafter more fully appear.

In the drawing chosen for the purpose of illustrating my invention, the scope whereof is pointed out in the claims, Figure 1 is a diagrammatic view of portions of a running board and portions of the front drivers of a locomotive, and, in perspective, the flange lubricator devices embodying my invention. Fig. 2 is a central sectional view of the lubricant conduit, the inclosing steam conduit, the valve casing, and in cross section the valve for controlling the flow of the lubricant. Fig. 3 is a detail sectional view of the lower ends of the lubricant and steam conduits and the valve casing taken at right angles to the section in Fig. 2, the valve being shown in elevation with parts broken out. Fig. 4 is a sectional view of the lubricant delivery nozzle provided with a needle for clearing the nozzle when obstructed. Fig. 5 is a sectional detail view of a modified form of valve for intermittently controlling the flow of the lubricant.

Like symbols refer to like parts wherever they occur.

I will now proceed to describe my invention more fully so that others skilled in the art to which it appertains may apply the same.

In the drawings, A indicates the running-board of a locomotive, a indicates the bottom line of the locomotive boiler, b a portion of the guide yoke, which is here selected as the point of support for the controlling valve and conduits of the apparatus though if desired or required any other suitable point of support therefor may be selected.

B, B', respectively, indicate the right and left front drivers of a locomotive to the flanges of which the lubricant is to be applied.

C indicates the cylinder, V the valve chest, and R the valve rod on one side of a locomotive.

A suitable lubricant reservoir 1 may be secured to the underside of the running board A by straps 1^a, or in equivalent manner, from which reservoir a lubricant conduit 2 leads the lubricant to an intermittently operated valve 3 provided for controlling the flow of the lubricant to the part to be lubricated.

4 indicates a steam conduit which may

receive its supply from any suitable source, and wherever available for the purpose steam from an exhaust may be utilized, as in this instance, where the steam may be taken from the exhaust of the air pump which is a common and well known adjunct of locomotives, and being such is not here shown. Through an enlargement 4^a of the steam conduit the lubricant conduit 2 passes to the lubricant controlling valve 3, and this enlargement of the steam conduit is preferably formed of a top or cap member 5 provided with a stuffing box 6 (or threaded nipple, annular cap, and packing rings) through which the lubricant conduit passes, and a bottom member 7 which constitutes the valve casing and into which the lower end of the lubricant conduit is screwed as at 7^a. The two heads of the cap and valve casing 5 and 7 are connected by the intermediate cylinder 4^a or enlarged portion of the conduit 4 which constitutes a steam chamber wherein the heat from the water of condensation and the exhaust steam will maintain the fluidity of the lubricant so that any grade of oil from coal oil to asphaltum may be utilized. The bottom member 7 which, as above noted, may also constitute the casing of the controlling valve 3 is provided with a port 8 leading therethrough from the lubricant conduit to the valve chamber 3^a and a port 8^a leading from the valve chamber to the delivery chamber 3^b, and said bottom member 7 is secured by a threaded bolt or set screw 7^c to a bracket 9 attached to the guide-yoke b, which latter has been selected as the point of support for the controlling valve and conduit.

The controlling valve 3 as shown in Figs. 1, 2 and 3 of the drawing, is preferably a three-way valve of the rotary type having the Y shape through ports 10 which, when the valve 3 is at rest in its normal position in the valve chamber 3^a of the casing, will prevent the simultaneous registration of the casing ports 8, 8^a with a through passage of the valve ports 10, as a result of which the lubricant is intermittently delivered into the delivery chamber 3^b when the valve is operating and no delivery is made when the valve is at rest in its normal position. The same result may be obtained by the use of a slide valve as indicated in Fig. 5 of the drawing in which case the slide is preferably of cylindrical form as at S and is provided with the peripheral grooves s and s', s', constituting valve ports which do not simultaneously register with the ports of the valve casing when the valve is at rest in its normal position.

The end walls 7^b of the valve chamber 3^a which project laterally of the casing member 7 are threaded for the reception of the end caps 11, 11^a, one of which, 11^a, in the case of a rotary valve (see Fig. 3) and

both of which in case of a slide valve (see Fig. 5) are perforated for the passage of the valve stem and suitable packing rings 11^b are inserted in the end caps to effectively pack the valves. It is also desirable to provide a supplemental closure end cap 11^c which may be carried by the closure end cap 11 (see Fig. 3), as the same will be found serviceable in case the casing ports 8, 8^a should become clogged, whereupon the cut-off 18^b will be turned to close conduit 18, the perforated cap 11^a and valve 3 can be removed, the supplemental cap 11^c substituted for annular cap 11^a and steam pressure utilized to clear the ports of any obstruction.

In case a rotary controlling valve is employed, as shown in Figs. 1, 2 and 3, a crank arm 12 may be connected by means of rod 13 with some moving portion of the machinery, as for instance with a valve stem R or a rocker arm, to obtain an automatic intermittent movement of the valve, and the connection should be so made that when the machine to which the lubricating devices are attached is at rest the controlling valve 3 will be normally closed.

In case a slide valve S is used, as indicated in Fig. 5 of the drawings, the connecting rod 13 may be made to reciprocate the slide valve S through the medium of a rocker arm or lever 14 having its fulcrum on a bracket 14^a secured to the casing member 7, which lever 14 is pivotally connected with the stem of slide valve S.

From the portion 4^a of the steam conduit which incloses the lubricant conduit 2 a continuation of the steam conduit marked 15 leads down and delivers into the lubricant delivery chamber 3^b below the controlling valve 3 and into which chamber 3^b the lubricant enters from casing port 8^a. The delivery end of conduit section 15 which enters delivery chamber 3^b is preferably in the form of a jet 16, and the T which connects the sections 15 and 16 of the conduit may have its outer end closed by a screw plug 17 to facilitate clearing of the jet should it from any cause become clogged.

18 indicates a continuation of the lubricant conduit which receives the lubricant and steam from the delivery chamber 3^b and through the medium of T connection 18^a and branch pipes 19, 19^a delivers the spray of lubricant and steam through nozzles 20 to the flanges of the drivers B, B'.

At 18^b is shown a cut-off cock in conduit section 18 leading from the delivery chamber 3^b, which cut-off cock is to be turned to close the conduit section 18, when obstructions are to be blown out of the valve and casing ports.

The nozzles 20 for jetting the lubricant on the part to be lubricated may be of any desired character, but preferably are, as indi-

cated in Fig. 4, comprised of the nozzle sections 20^a, a T coupling 20^b by means of which connection is made with conduit section 19 or 19^a, and a perforated screw plug 5 20^c which carries a spring-supported needle 21 centered in the nozzle and by pressure on which any plugging or obstruction of the nozzle can be displaced.

The operation of the foregoing devices 10 will be found simple, effective, and automatic, requiring no attention other than to fill the reservoir, when required.

When the mechanism is at rest the valve 3 which controls the intermittent delivery of 15 the lubricant will be normally closed; when the machine is in operation, the exhaust steam, or its equivalent, will pass by conduit 4 to conduit section 4^a which incloses the lubricant conduit 2 and thence by conduit 20 section 15 and jet 16 into delivery chamber 3^b, and the valve 3 being simultaneously actuated from some movable portion of the mechanism, intermittently delivers the lubricant into delivery chamber 3^b, where it is 25 taken up, sprayed and carried by the steam which enters said chamber from conduit section 16, into conduit section 18, branches 30 19, 19^a, and projected through nozzles 20 onto the flanges of the drivers B, B', or such portions of the machinery as are to be lubricated.

Having thus described my invention, what I claim and desire to secure by Letters Patent is:

35 1. In a lubricating device, a lubricant conduit which leads to the part to be lubricated, an intermittently actuated valve which controls the flow of the lubricant through the lubricant conduit, a conduit for steam which 40 incloses the lubricant conduit and delivers thereinto at a point between the valve and the part to be lubricated, and means for operatively connecting the valve with a moving part of the machine.

Copies of this patent may be obtained for five cents each, by addressing the "Commissioner of Patents, Washington, D. C."

2. In a lubricating device, the combination of a lubricant conduit, a valve casing having a valve chamber and a delivery chamber and provided with ports which connect the lubricant conduit with the valve chamber of the casing and the valve chamber with the delivery chamber thereof, a steam conduit which discharges into the delivery chamber of the casing, a valve having ports which alternately register with the port leading from the lubricant conduit to the valve chamber, and means for actuating the valve from a moving portion of the machine.

3. In a lubricating device, the combination of a lubricant conduit, a valve for intermittently controlling the flow of lubricant through the conduit, a valve casing having a valve chamber and a delivery chamber which connects therewith, a steam conduit which incloses the lubricant conduit and is provided with a jet which enters the delivery chamber of the valve casing, and means for operatively connecting the valve with a moving part of the machine.

4. In a lubricating device, the combination of a lubricating conduit which leads to the part to be lubricated, a valve casing interposed in the lubricating conduit, said valve casing provided with ports and having a valve chamber provided with end caps, and a delivery chamber, a cut off cock interposed in the lubricant conduit between the valve casing and the point to be lubricated, and a steam conduit having a jet which enters the delivery chamber of the valve casing.

In testimony whereof I affix my signature, in the presence of two subscribing witnesses.

THOMAS J. CLAYTON.
